UNITED STATES PATENT OFFICE.

CLARENCE SCHOCK, OF MOUNT JOY, PENNSYLVANIA.

COAL-CHUTE.

1,311,622.

Specification of Letters Patent. Patented July 29, 1919.

Application filed May 25, 1917, Serial No. 170,976. Renewed March 16, 1918. Serial No. 222,984.

To all whom it may concern:

Be it known that I, CLARENCE SCHOCK, a citizen of the United States, residing at Mount Joy, in the county of Lancaster and State of Pennsylvania, have invented certain new and useful Improvements in Coal-Chutes; and I do hereby declare the following to be a full, clear, and exact description of the invention, such as will enable others skilled in the art to which it appertains to make and use the same.

My invention relates to new and useful improvements in coal chutes and more particularly to that class adapted to be used in connection with storage plants or "coal pockets" and my object is to provide a chute of this class whereby anthracite coal or any fragile granular material may be lowered from any height and the breakage or disintegration of the particles of coal or other fragile material reduced to a minimum. This object I attain by so constructing the chute that a portion of the coal will accumulate in the angle formed by the wall and flooring of the chute, thereby providing a bed of coal over which the rest of the coal travels and offering resistance to the flow of the coal sufficient to prevent violent or rapid movement or impact which would result in undue breakage, the resistance caused by the accumulated coal in the angle formed by the wall and flooring results in the coal flowing down the same way as it would naturally do on the side of a pile without the danger of breaking or disintegrating the particles of the coal.

Another object of this invention is to provide the chute with a novel form of feeding hopper.

Another object is to provide a storage bin or the like for the coal chute, whereby the stored coal which has been delivered thereto by the chute may be conveniently loaded into wagons, cars, or like vehicles.

These and other objects and advantages will more fully appear as the nature of the invention is more clearly understood from the following description taken in connection with the several views of the accompanying drawings wherein I have disclosed one embodiment of my invention, but which is susceptible to numerous alterations and variations therein from time to time to meet the exigencies of the case without departing

from the spirit of the invention or exceeding the scope of the appended claims.

In the drawings,

Figure 1 is a side elevation of the chute.

Fig. 2 is a side elevation of the construction forming the base of the chute.

Fig. 3 is a top view of the structure shown in Fig. 2.

Fig. 4 is a fragmentary side view of the upper portion of the chute showing another form of feeding hopper which I may employ.

Fig. 5 is a fragmentary side view of the lower portion of the chute, showing the same in operative position upon a storage bin or the like.

I desire to here state that for the purpose of clearness and convenience in illustrating my invention I have adopted the form and construction shown in the drawings and will specifically describe the same, but it is to be understood that I am not to be limited to the exact form, construction and arrangement of the parts nor to the character of materials, the dimensions of the parts, nor the specific manner of assembling and securing together of the parts as hereinafter described, as I may form the parts of the chute of any suitable material such as wood, metal, concrete, or plastic composition and of any suitable and desired dimensions of the parts as well as construct the chute of any desired width and height by increasing or decreasing the number of the parts thereof.

Referring to the drawings, wherein similar reference characters denote corresponding parts throughout the several views, 1 denotes the base or sill of the chute which is preferably formed in the shape of a ring and suitably secured upon the base or sill 1, as by mortising and the like, are the timbers 2 which form the first tier of standards of the chute. These standards 2, for example, are three inches by four inches in cross measurements, but the standards 2 are formed of different lengths, for instance, there is shown, for illustration, sixteen of these standards 2, the first or shortest standard being preferably two feet long, while each subsequent standard is formed six inches longer than the next preceding standard, so that the last or longest standard will be nine and one-half feet long. By so forming the standards 2, their upper ends from

the shortest to the longest will terminate in a manner to form an upward spiral course. This constitutes the base portion or first tier of standards for the beginning of the 5 construction of the chute.

Upon the upper ends of the standards 2 are positioned the lower ends of the timbers or standards 3 of the second tier of standards. These standards 3 are also formed 10 three inches by four inches in cross measurements, but these standards 3, in practice, are all formed of the same length eight feet or a multiple of eight feet in this instance, but for the sake of illustration these standards 15 have been shown in the drawings as being eight feet long. However, certain of these standards 3 have been shown slightly shorter than the others in the drawings due to the lack of space, and in order to illustrate 20 the construction of the upper portion of the chute, the lower ends of the standards 3 are secured to the upper ends of the standards 2 and in vertical alinement therewith by the clamping plates 4 through which and 25 the contiguous ends of the standards 2 and 3 project a plurality of bolts 5 or other suitable securing means. However, these ends of the standards 2 and 3 may be secured together in any other suitable manner as by 30 mortising, tonguing and grooving, or splicing and the like.

Any number of tiers of the standards 3 may be placed one upon the other until the chute has been built up to the desired height, 35 but the single tier of standards 3, as shown in the drawings, will suffice to illustrate the purposes and intent of the invention, and with this object in view, which is believed to be clearly set forth, there is shown positioned upon the upper ends of the standards 3 the third or finishing tier of standards 6 40 having their lower ends secured to the upper ends of the standards 3 of the second tier in the same manner that the lower ends 45 of the standards 3 are secured to the upper ends of the standards 2. The standards 6 of the final tier are formed, however, of such lengths and in the reverse order of the standards 2 of the first tier so that their 50 upper ends will lie substantially in a horizontal plane for receiving the plate 7 which is suitably secured upon the upper ends of the standards 6 and which may be formed of any desirable shape so long as there is 55 an ample central opening therethrough for discharging coal or other fragile material into the intake hopper formed in the upper portion of the standards 6 of the upper tier, the hopper comprising the annular side wall 60 8 secured to the inner sides of the standards 6 in any suitable manner and is formed with the straight upper edge which preferably contacts with the under surface of the plate 7 and the lower inclined edge 9 upon which 65 is secured the inclined bottom 10 which is

reinforced by the supporting band 11 therebeneath and which band 11 is suitably secured to the adjacent inner surfaces of the standards 6, the band 11 also reinforcing the standards 6 in addition to the reinforcing struts or brace bars 12 suitably secured to and spacing the upper ends of the standards 6.

The foregoing describes the main frame of the chute and within this frame are the 75 plurality of superimposed supporting bars 14 formed, as for example, six inches in width and of any suitable thickness and disposed one above the other in vertical edge-wise position. The bars 14 have one of their 80 ends secured to one side of the respective standards 2, 3 and 6 and have their opposite ends suitably secured upon the side of one of the standards 2, 3 or 6 diametrically opposite to the standards to which the first- 85 mentioned ends of the bars 14 are secured, the bars 14 being disposed diametrically across from standard to standard in an upwardly inclined direction and preferably 90 inclined substantially six inches to the foot or at an angle of substantially twenty-two and one-half degrees and have their respective ends secured to the same or corresponding sides of the standards 2, 3 and 6 and each successive bar 14 is disposed so that its 95 lower edge will lie approximately in the same conical surface with the upper edge of the next preceding bar but with the upper edge of each successive bar being elevated above the upper edge of the next preceding 100 bar substantially six inches thereabove and as the standards 2, 3 and 6 are, for example, spaced twelve inches apart from center to center, the respective ends of the bars 14 105 will be advanced in an upward spiral direction, so that the bars 14 will cross each other at a point along the vertical axis of the chute and provide main bracing members for the respective standards 2, 3 and 6. For 110 example, the lowermost end of the lowermost bar 14 is secured upon a side of the shortest of the standards 2 at any suitable point above the base or sill 1 of the chute and extends obliquely upwardly at an inclination of substantially twenty-two and 115 one-half degrees or a rise of approximately six inches to the foot and has its opposite or uppermost end secured to a corresponding side of the standard diametrically opposite to the shortest standard 2, and the successive bars are likewise secured to each 120 succeeding pair of standards upwardly to the upper portion of the chute or until the uppermost bar 14 contacts with the bottom 10 of the hopper, and at one side of the opening 15 formed in the bottom 10 of the hopper, which opening is controlled by the sliding valve or gate 16 actuated by the rod 17.

As it is preferable to also reinforce the 130

standards 3 of the second or intermediate tier to insure their stability, the reinforcing struts or space bars 13 are provided which are secured to and efficiently space the standards 3 at any suitable and desirable point but preferably in a manner to position the reinforcing struts or space bars 13 in horizontal alignment with each other.

The diagonal braces 14 act both as supporting members for the floor of the chute and reinforcing members for preventing lateral movement of the standards 2, 3 and 6. The addition of the space bars 13 which act as wedges and are driven in place from the outside of and to place between the standards 3, puts a tension on braces 14 and makes the whole structure taut and rigid. Braces 14 are put in place first and the wedging space bars 13 are put in place afterward, the last one of each circle of the bars 13 being driven home tight and making the complete circle taut and rigid. This method of structure with the braces 14 of correct length and correctly located on standards 2, 3 and 6, and followed by insertion of the wedging brace bars 13 not only makes a rigid construction but insures the perpendicular of the structure. If the base to start with is level and all parts are correctly cut and placed, the structure must come plumb; it will not go together any other way.

Secured upon the inner sides of the standards 2, 3 and 6 and connecting the standards in pairs are the plurality of cleats 18 being horizontally disposed with their upper edges lying in a plane with the upper edge of the lower preceding bar 14 but beneath the lower edge of the next upper succeeding bar 14. The cleats 18 not only aid materially in reinforcing the standards 2, 3 and 6 but also provide supports for the lower ends of the bars 14.

Suitably secured upon the upper edges of the bars 14 and the upper edges of the cleats 18 are the steps 19 constituting the spiral floor of the chute. These steps or treads 19 are of substantially triangular form and extend from the inner sides of the standards 2, 3 and 6 upwardly and inwardly along the lowermost inclined portions of the bars 14 and have their apexes at the vertical axis of the chute, that is, at the point where the bars 14 intersect and cross each other. These steps forming the spiral floor of the chute are, for example, twelve inches wide at their outer ends and gradually diminish in width until they become pointed at the vertical axis of the chute, but each step 19 is elevated above the other at approximately six inches, having what is commonly known as a six inch rise.

To prevent the material, such as coal or other fragile material, from sliding off the outer ends of the steps or treads 19 of the chute flooring, the end walls 20 are provided

and formed of a sufficient height to meet the needs of a given case, and while I have shown as individual wall for each step or tread 19, I may form a continuous spiral wall from the top to the bottom of the chute. By so forming the steps of the chute flooring, the same is inclined downwardly and outwardly from the vertical axis of the chute to its periphery, so that when coal or other fragile material is discharged through the opening 15 of the hopper upon the uppermost step 19 the coal is forced to flow to the outer edge or periphery of the spiral stepped floor, where it lodges in the stepped V-shaped trough formed by the sloping steps 19 and the retaining wall 20. The pitch of the spiral flow at its outer edge or periphery should be less than the angle of flow of the material to be lowered. The surface of the floor, being stepped prevents the coal from sliding as would be the case if the floor of the chute were a smooth steel helical surface. Furthermore, the angle between the sloping floor 19 and the retaining walls 20 act as a wedge to hold a body of coal. This body of coal or other material will be retained until the increased quantity of it brings the inner spiral edge of the body of coal closer to the central axis of the chute, and consequently into a steeper pitch until this inner edge of the retained body of coal or other material reaches a pitch equal to or slightly greater than its natural angle of flow, and then it will flow down spirally just as it would flow down on the side of a large pile. The step underneath the coal will be practically invisible and the flow will be smooth and natural and at an easy speed. As the flowing coal reaches the top of the accumulated pile around its base it will come easily and at an almost imperceptible angle into contact with the surface of such pile. When the bed of coal in the chute is complete from top to bottom, the flow of additional coal down the chute is just as natural as on the side of a pile.

In the construction herein shown the pitch of the helicoid surface at periphery is 6 inches to the foot. The steps 19 reach to a point in line with the vertical axis and here the helicoid surface reaches its vertical limit. For the lowering of coal these steps would not need to extend inward from the wall 20 more than one-half the distance to the central axis. Such construction would provide a pitch of 12 inches to the foot or 45 degrees at the inner edge of the steps or helicoid surface which would be amply steep enough to provide room for movement of the coal without spilling over, the natural angle of flow of anthracite coal being somewhere between 25 degrees and 30 degrees.

The chute is constructed with steps reaching to the central axis for the purpose of 130

making it stronger, the steps so made increasing the strength. The steps need only extend toward the central axis far enough to provide a slope sufficiently steeper than 5 natural angle of flow of material to insure safe lowering flow without spilling over the inner edge and falling a distance sufficient to cause undue breakage.

Other forms of floor can be used, the 10 width of steps can be decreased, the height of each rise can be made less, steps could be made two inches wide and rises one inch high, or the floor could be a true helical surface of metal or plastic material sloping 15 radially from central axis to periphery. The elemental idea is the same as in a spiral stair-case with the notable difference of the sloping steps from axis to periphery, radially. The spiral stair-case is generally built 20 with a central post or its equivalent. If this chute were built after the manner of the spiral stair-case the diagonal braces 14 would terminate at the central axis and this central axis would be a round post to which 25 such half length braces 14 would be attached. It was in an attempt to so build this chute that the idea of running the braces 14 clear across to the opposite standard was discovered. It makes all the difference in the 30 world in the staunch construction of the spiral steps or helical surface whichever it may be or be designated. All other forms of construction as usually employed in spiral construction were practical failures in economy of cost, strength and endurance.

In lieu of the hopper shown in Fig. 1, I 35 may employ the hopper shown in Fig. 4 of the drawings and in this instance there is provided in the upper portion of the chute 40 and extending obliquely to one side from the upper edge of the uppermost of the bars 14 to the plate 7 the inclined wall 21 to prevent the coal from falling through the wrong side of the chute, and positioned within the 45 opening of the plate 7 is the cone-shaped hopper 22 provided around its upper edge with the outwardly extending flange 23 adapted to rest upon the upper surface of the plate 7. Pivotaly mounted upon the 50 hopper 22 and beneath the central opening therein is one end of the trough 24 having suitably secured upon its discharge end 25 the chain, cord, or other suitable means 26 for raising and lowering the discharge end 55 25 of the trough 24, and in this instance when the discharge end 25 of the trough 24 is lowered, the coal from the hopper 22 will be discharged upon the uppermost step 19 and the coal will flow downwardly 60 through the chute in the manner above described.

In Fig. 5 I have shown one of the several means which I may employ for delivering the coal from the chute into a repository, 65 and in this instance I show the bin 27 in

which the lower portion of the chute is mounted, and the bin 27 is supported a sufficient distance above the ground by the frame 28 supported by any suitable number of standards 29 suitably braced to the frame 70 28 by the diagonal bars 30. Upon the bottom of the bin 27 and extending for a distance therebelow is the cone-shaped hopper 31 provided with the discharge spout 32, the opening of which is controlled by the swinging gate 33 actuated by the handle 34, so that when the gate is swung around sufficiently to open the spout 32, the coal or other fragile material may be discharged into a wagon 35 driven therebeneath, or in lieu 80 of the wagon 35, the coal may be loaded upon a railroad car upon tracks which may be laid to pass between the standards 29 and beneath the hopper 31 of the bin 27.

In my chute my plan has been to provide 85 a chute on which the coal will roll down or flow down as it naturally does on a large pile; and at the same time construct it at a pitch equal to or greater than the natural repose or the angle of flow so as to avoid 90 any possible congestion at the bottom of the chute. I accomplish this result by giving the chute a lateral pitch from the vertical axis or central supporting members to the lower edge of the retaining wall or 95 spiral flange, thereby directing the coal from the vertical axis or the central supporting members against the outer wall or flange, insuring the descent of the coal at the lowest angle of pitch on the helicoid surface thereof at which it will flow, the floor of the chute and the wall or flange forming a substantially V-shaped trough in which the coal will bind in its descent and retain a sufficient bed of coal from top to bottom 100 of the chute to cause the descending coal to roll or flow down naturally as it does on a large pile, thereby enabling me to construct the chute with a circular pitch at the inner edge of the helicoid surface equal to or 105 greater than the natural angle of flow of the coal.

Furthermore, if the helicoid surface of my chute be made sufficiently wide, the same chute will be adapted to different sizes and 110 kinds of coal, having different natural angles of flow, just so the pitch is not too steep at the periphery of the helicoid surface to insure the retention of a sufficient bed of coal for the size or kind which flows at the lowest 115 angle. In case of coal flowing at a steeper angle, the chute will simply retain a larger or wider continuous bed of coal from top to bottom, and the increased pitch of the helicoid surface as it approaches the central axis 120 will insure the easy and natural flow of the coal requiring a steeper pitch.

In chutes of that class where the circular pitch is less than the natural flow of the coal 130 it will be seen that when the bin or pocket

has been filled with coal the whole weight of the volume of coal will be directed upon the chute upon starting to remove the coal from the bin and unless the chute is substantially braced it will be crushed by the weight of the coal, while in my construction the volume of coal would move off the chute at its natural flow thereby producing no undue weight thereon.

- 10 By this construction the coal or other material will flow in a continuous stream around the chute and over the floor of the bin without any sudden stops or falls and will continue its equal flow from the top 15 to the bottom of the chute at whatever height the chute may be built.

When the chute is constructed as shown in the several views, the pitch of the chute floor adjacent the central axis will be greater 20 than at the outer end of the floor, so that should materials descending in the chute for any reason become clogged in the V-shaped portion thereof, that portion of the volume of material adjacent the column 25 will continue to flow incident to the increased pitch of the floor, but at its natural angle of flow, owing to the accumulation of material in the V-shaped portion of the chute.

- 30 Having described my invention, what I claim as new and desire to secure by Letters Patent, is:—

1. A vertical spiral chute with downward lateral slope from its axis, the spiral pitch of 35 the chute at its axial edge being greater than the natural angle of flow of the material conveyed, and the spiral pitch of the chute at its periphery being less than the natural angle of flow of the material conveyed.

40 2. A chute comprising a spiral floor and walls for said floor, said floor and said walls being composed of sections and secured together, the sections of the floor sloping laterally from the inner edge to the periphery, 45 the spiral pitch of the floor adjacent the inner edge being steeper than the natural angle of flow of the material conveyed, and the spiral pitch of the chute at its periphery being less than the natural angle of flow of the 50 material conveyed.

55 3. A vertical, spiral or helicoid chute with downward, lateral slope from the inner edge to the periphery, and a retaining wall attached to the periphery of said chute, the surface of said chute being at an acute angle with the wall, the spiral pitch of said surface at its inner edge being steeper than the natural angle of flow of the material conveyed, and the spiral pitch of the chute at 60 its periphery being less than the natural angle of flow of the material conveyed.

4. A spiral chute the floor of which is formed in sections, said sections sloping downwardly in a radial line from their inner edges to their peripheries, said sections

being in stepped relation to each other at inner edge and periphery.

5. A spiral chute having a floor formed of sections arranged in stepped relation to each other and having their entire surfaces horizontal in the circular direction of the floor, each of said surfaces sloping downwardly in a radial line from the inner edge to the periphery. 70

6. A spiral chute having a floor formed of 75 sections arranged in stepped relation to each other and having their entire surfaces horizontal in the circular direction of the floor but sloping downwardly in a radial line from the inner edge to the periphery, the 80 spiral pitch of the floor adjacent the inner edge being greater than the natural angle of flow of the material conveyed.

7. A spiral or helical chute, comprising a base, standards upon said base, bars connecting 85 said standards, a floor upon said bars, and a hopper upon said standards for delivering material to said floor to be conveyed to said base.

8. A spiral or helical chute, comprising an 90 open base, standards upon said open base in spaced relation to the vertical axis of the chute, inclined bars connecting said standards, a stepped spiral floor upon said inclined bars and sloping downwardly from 95 axis to periphery, and a wall at the outer edge of said spiral floor.

9. A spiral or helical chute, comprising an open base, a plurality of standards upon 100 said open base in spaced concentric relation to the vertical axis of the chute, a plurality of transverse inclined bars connecting the oppositely disposed standards in pairs, a stepped spiral floor upon the lower portions of said transverse inclined bars and sloping 105 downwardly from axial edge to periphery, and a wall at the outer edge of said spiral floor.

10. A spiral or helical chute, comprising an open base, a plurality of sectional standards upon said open base in spaced concentric relation to the vertical axis of the chute, said standards being formed to position their joints in a stepped spiral course, a plurality of inclined superimposed supporting and reinforcing bars consecutively crossing each other in the line of the vertical axis of the chute and consecutively connecting two of the diametrically opposite sectional standards in proximity to their joints, a stepped 110 spiral floor upon the lower portions of said inclined bars and sloping downwardly in radial line from the inner edge to the periphery, and a wall at the outer edge of said sectional spiral floor. 115

11. A spiral chute comprising a plurality of standards in spaced concentric relation to the vertical axis of the chute, a plurality of transverse inclined bars connecting the oppositely disposed standards in pairs, and a 120 125 130

- stepped spiral floor upon the lower portions of said transverse inclined bars, the surface of the floor sloping downwardly from the inner edge to the periphery.
- 5 12. A spiral chute comprising a plurality of standards in spaced concentric relation to the vertical axis of the chute, a spiral floor formed in sections, and a plurality of transverse inclined bars connecting the oppositely disposed standards and forming a support for the sections of the floor.
- 10 13. In a vertical spiral chute constructed to retain a portion of the material con-

veyed, a floor with downward lateral slope from its axis, the spiral pitch of the chute 15 at its axial edge being greater than the natural angle of flow of the material conveyed.

In testimony whereof I have signed my name to this specification in the presence of 20 two subscribing witnesses.

CLARENCE SCHOCK.
